MULTIPLE PRINTING MACHINE

John L. Goines, Albert C. Goines, and Charles S. Goines, Charlotte, and Roy E. Heward and George S. Holland, Concord, N. C.; said Howard and said Holland assignors to said John L. Goines, said Albert C. Goines, and said Charles S. Goines.

Application May 9, 1944, Serial No. 534,778

1 Claim. (Cl. 101—199)

1

The object of our invention is to provide a novel multiple printing machine, having a plurality of type beds, synchronously operated inking rollers and means for conveying strips of paper from a series of paper rolls over the type beds and printing on the separate strips of paper the desired printing and thence automatically feeding these several strips of paper to a cutter and cutting them into the desired page sizes and in combination with this mechanism; perforating these pages along a pre-determined line or lines and automatically folding the pages and forming them into folders, pamphlets or books, as more fully hereinafter described.

It is also our object to provide novel means for operating this multiple printing machine and to provide novel means for adjusting and regulating its operation.

We attain these and other objectives of our invention by the mechanism illustrated in the accompanying drawings in which:

Figure 1 is a side elevation of the major portion of the machine;

Fig. 2 is a continuation of the side elevation shown in Fig. 1 showing the end of the machine which perforates the several strips of the paper either or both longitudinally and transversely and cuts them into sheets of the desired size;

Fig. 3 is a side elevation of the remaining upper portion of the machine which because of its height could not be shown in Fig. 2 and constitutes a continuation of Fig. 2, the purpose of which is to unwind the paper from the large paper rolls 60, 61, 62, 63;

Fig. 4 is a sectional view of an enlarged scale of the top roller system at the extreme right end of the machine;

Fig. 5 is a detail of the wheel that keeps the paper tight against the roller, corresponding with the mechanism shown in Fig. 3;

Fig. 6 is a section on Fig. 1 with certain parts omitted for clarity;

Fig. 7 is a continuation of the section shown in Fig. 6;

Fig. 8 is a detailed elevation showing the source of power for the driving shaft to turn the ink discs;

Fig. 9 is a section of the ink well shown at the upper left hand corner of Fig. 7 and which is the

original source of the ink before it is spread on the inking discs and type for printing;

Fig. 10 is a continuation of the sectional view shown in Figs. 6 and 7;

Fig. 11 is a view of the paper size regulator which is also illustrated on a smaller scale in Fig. 2 in connection with other parts;

Fig. 12 is a section on line 12—12 of Fig. 11;

Fig. 13 is a section showing how the large roll of paper shown in Fig. 10 is attached on the shaft to any desired position. The large roll of paper may turn either on or with the shaft.

Fig. 14 is a side elevation of the power-driving mechanism which is the original source of power of the machine;

Fig. 15 is a detailed perspective view of the type bed with the impression plate swung back into open position;

Fig. 16 is a perspective view of the impression plate in operating position.

Fig. 17 is a small detail of the locking pins for securing the chase to the type bed.

Fig. 18 is a view partly in elevation and partly in section, showing how the impression plate is supported when it is in open position;

Fig. 19 is a diagrammatic top plan view showing the inking mechanism when the inking is first begun;

Fig. 20 is a similar diagrammatic top plan view showing the position of the rollers when spreading ink over one of the inking discs;

Fig. 21 is a similar diagrammatic top plan showing the rollers in a position where they again pick up ink, and also showing the area covered by the ink when the rollers are in contact with the first inking disc;

Fig. 22 is a similar diagrammatic top plan view of the rollers in contact with the second inking disc, spreading the ink and also illustrating the point where the ink will have to be deposited before the other two rollers pick it up and carry it across to the opposite disc; the two rollers 31 (Fig. 22) convey the ink on their right side ends from ink discs 15 to ink discs 32 without depositing any ink on the type. Therefore ink discs 32 contain the same amount of ink as ink discs 15, and all sides of the type is uniformly covered with ink;

Fig. 23 is a diagram of one of the inking discs showing how the ink is spread over its surface due

to its revolution as the inking roller passes over it;

Fig. 24 is a diagrammatic side elevational view showing the whole system of rollers and the manner in which the strips of paper from the primary rolls are threaded over the various conveying or loose rollers, when using four sheets or rolls of paper and three sheets of carbon paper;

Fig. 25 is a similar diagrammatic side elevational view of the whole system of rollers but illustrating the operation when only two rolls of paper are used and both sides of the paper are being printed, with carbon paper dispersed between the two printed sheets.

Fig. 26 is a small detail perspective view of our floating tension bar which by reason of its weight holds the strip of paper in the desired position to engage the nearest rollers;

Fig. 27 is a section longitudinally of a portion of the printing machine near the end of the machine where the paper is perforated and where it is cut into sheets or pages by the automatically operated knife and then deposited on a conveyor belt;

Fig. 28 is a transverse elevational view taken approximately on the line 28—28 of Fig. 27 to show the relationship of the rollers and gears;

Fig. 29 is a side elevation taken approximately on line 29—29 of Fig. 28;

Fig. 30 is a detail side elevation of the large ratchet delivery wheel taken approximately on line 30—30 of Fig. 28;

Fig. 31 is a perspective view of the parallel perforator 81 shown on Fig. 27;

Fig. 32 is a perspective view showing the transverse or cross-perforator mechanism 174 shown in Fig. 27 and adjacent mechanism, also means have been provided whereby this perforator can be operated when same is mounted on frame 64 between either of the rollers 84 in Fig. 24;

Fig. 33 is a side elevation of a mechanism for moving the conveyor belt and depositing the sheets or pages of paper after they have been cut from the several strips;

Fig. 34 is a perspective view of the conveyor belt and tray into which the sheets of paper are deposited after they have been printed and cut into the desired pages;

Fig. 35 is a detailed sectional view showing how a divided shaft is brought into operating engagement to function in order to move the conveyor belt;

Fig. 36 is a side elevation of the large ratchet counting wheel which has a pre-determined number of teeth, preferably numbered 1 to 100, the view also showing four lugs which engage a lug shown in Fig. 37 which moves the long rod shown in Fig. 33, thereby engaging the two shafts shown in that same view and causing the conveyor belt to move;

Fig. 37 is a perspective view showing the means of attachment for the lug which contacts one or several lugs shown on the ratchet counting wheel illustrated in Fig. 36 and which causes the long shaft shown in Fig. 33 to move;

Fig. 38 is a small detail perspective view showing the U-shaped rod at the end of the long shaft shown in Fig. 33 and functioning to engage the gears 123g and move the belt;

Fig. 39 is an elevational view of the paper severing knife and its automatically actuating mechanism taken in a plane transverse of the machine immediately adjacent said knife and knife operating mechanism;

Fig. 40 is an elevational view showing the gate mechanism which clamps the paper in stationary

position when the knife cuts the paper and while the perforator passes across it, and the mechanism which operates this gate;

Fig. 41 is a detailed sectional view on line 41—41 of Fig. 39;

Fig. 42 is a detail elevational view showing how the speed of the paper is regulated in passing over the rollers shown in Figs. 3 and 4;

Fig. 43 is a plan view taken on line 43—43 of Fig. 42;

Fig. 44 is a perspective view of one of the four rollers shown at the lower right hand end of the printing machine in Fig. 2;

Fig. 45 is a section of the rollers between the type beds and impression plate;

Fig. 46 is a detail perspective view of a portion of the paper tension regulator shown on Fig. 2;

Fig. 47 is a perspective view partly in section and partly in elevation showing how the perforator is attached to the machine, this mechanism also is to regulate the printed impression with the shearing knife;

Figure 47A is a view, partly in section, of the means employed to secure the perforating mechanism in adjusted position.

Fig. 48 is a small detail section in a plane on a median longitudinal line with the shaft which supports the perforating disc 168;

Fig. 49 is a perspective view showing the roller which pulls the carbon off the large carbon rolls or other original source of supply of the carbon. This mechanism is also shown on Fig. 1 in three different positions, where three rolls of carbon paper are used;

Fig. 50 is a detail front plan of a brake on the opposite end of shaft 93 from the ratchet wheel; and

Fig. 51 is a side elevation of the brake shown in Fig. 50. Like characters of reference designate like parts in each of the several views.

As shown in Fig. 14 an electric motor 1 is belted to a wheel 2, on a shaft 3, carrying a pulley 4, which in turn is belted to and drives a large pulley 5 which has a shaft 6 carrying a small gear 7 which meshes with a large gear 8 which drive the main shaft 9. Shaft 9 runs lengthwise of the machine. Shaft 9 carries four large cams 10, each having opposite projections 11 which engage rollers 12 that are mounted on the bottom of the four type beds 13, the cams 10 being arranged to rise successively so that only one of the type beds prints at a time.

As shown in Fig. 15, Fig. 6 and Fig. 1, the type beds 13 are returned to lowered position by the springs 13a, thereby removing the type from contact with the paper, which is against impression plate 23. When the type is in contact with the paper which is against the impression plate 23 the type bed 13 moves down only enough to permit the rollers 31 to pass between the type and impression plate. This short movement enables the press to run at a very high speed. Also this movement enables the ink rollers 31 to pass over and deposit ink on the type held in type chase 14. (Fig. 15).

The type on these type beds is mounted in an adjustable chase 14. This chase 14 is loosely seated on the type bed 13. Two opposed L-shaped fingers 16 engage the sides 17 of the chase, and a bolt 18 at one end adjustably engages a recess in the end 19 of the chase. A pin 21 (Fig. 17) extends through the frame of the chase at the other end 22 (shown in Fig. 6) to fasten it to a recess 20 (Fig. 15) to the bed plate 13.

In Figs. 19, 20, 21 and 22 is a flat metal plate

15a. The ink-conveying roller 33 rolls over said plate, the purpose of which is to help break up and thoroughly mix the ink.

The impression plate 24 and tympan or make-ready or draw sheet 23 are positioned immediately over the type bed 13. It is hinged at 25 at the front end to be swung to reversed position, as shown in Fig. 18, where it is supported by the bar 24a inserted in an opening in the supporting frame 64 of the machine. This part of the frame 64 which runs along the front part of the machine is shown in Figs. 1 and 2. It carries a rod 26 with an eye on each end hingedly mounted to the impression plate 23, to hold the impression plate 23 in place to cushion the type printing, shown in Fig. 6. The impression plate 23 is fastened in its normal position by two hinged bolts 27, and bolts 27a. Bolts 27 and 27a carry nuts 28, 28a, 28b, and 28c, respectively, to support the impression plate 23 in any adjusted position over the type bed 13. Rollers 23a (Fig. 15) on opposite sides of the impression plate 23 facilitate the travel of the paper around the impression plate 23. Clamps 23b (Fig. 15) hold the temporary or make-ready sheet to impression plate 23. Space 12a (Fig. 15) is a gate for the passage of paper through the type bed.

Referring to Fig. 6, two spaced bars 29 which function as tracks run along beside each impression plate 23. On these tracks 29 bearings 30 (blocks of metal recessed to engage the bar tracks) slide. These bearings 30 carry spaced rubber rollers 31 which function as inking rollers. There is an inking disc 32 just beyond the type bed and an ink-conveying roller 33 which travels over inking disc 15. This ink-conveying roller 33 is carried by rods 34 which are hingedly connected at 35 to the bearings 30 (Fig. 6) of the first-mentioned front inking rollers 31. Small spiral springs 37 (Fig. 6) on rods 34 cushion the shock when the ink-conveying roller 33 strikes the ink fountain roller 28, which is mounted at the end of the ink fountain 39 (Fig. 9), for each of the four sets of type beds. An ink disc 32 at the front of the machine, Fig. 6, just in front of the type bed and in horizontal alignment with it, has a depending central shaft 41, carrying a pulley 42, which carries a belt 43 that runs to a corresponding pulley 44. On the rear of the machine there is a corresponding depending rear shaft 40, having other functions.

In Fig. 6, the two contiguous inking rollers 31 run first over inking disc 15, then over the type, then over the inking disc 32, and then return in a reciprocal movement. The ink discs rotate in the same direction. The ink conveying roller 33 carries the ink over about one-third of the ink disc 15 nearest the ink fountain. Then the inking rollers when the ink has reached the point shown in Fig. 23, pick the ink up and carry it to the front ink disc 32, during the period that the type bed is lowered out of position to be engaged by the rollers.

Thus the ink is evenly distributed on the ink disc farthest from the fountain and nearest the front of the machine before it is spread by the rollers over the type. The inking rollers 31 hit the front disc when it has turned only a little ways, as the ink disc turns slowly, so that the ink is evenly spread over the disc and consequently over the type.

As shown in Fig. 6, each of the four rear ink discs 15 have their shafts 40 extended downwardly and carry at their lower ends a bevel gear 45 which meshes with a corresponding bevel gear 46 on a

shaft 47 running lengthwise of the machine. Shaft 47 carries a worm gear 48 (shown in Fig. 8) at the head end of the machine. This worm gear 48 meshes with a worm 49 on a transverse shaft 50 which at the front of the machine carries a sprocket 51. A sprocket chain 52 operatively connects this sprocket wheel 51 with a sprocket wheel 36 (Fig. 8) on a transverse shaft 53 on which is carried a small bevel gear 54. Bevel gear 54 meshes with a bevel gear 55 on stub shaft 56 which also carries a sprocket 57 (Fig. 2). A sprocket chain 58 on sprocket 57 operatively connects it with a sprocket 59 on the main driving shaft 9 near the head end of the machine.

15 As shown in Figs. 24 and 25, four paper rolls 60, 61, 62 and 63, are mounted on the elevated portion of the framework 64, over the machine. (64 refers to the supporting frame in its entirety whenever used.) Paper strips 65, 65a, 65b and 65c, from paper rolls 60, 61, 62 and 63, respectively, travel to the head of the machine and thence over four large spaced elevated mechanically driven rollers 66 and four smaller rollers 66a. Rollers 66 are geared together and turn at the same speed. The paper that passes over each of these rollers is engaged by smaller rollers 67 (Figs. 4 and 5), which are mounted on frame 70 carried by transverse rods 69, mounted in the frame 70 that holds the rollers. These transverse rods 69 have upturned ends 71, to which springs 72 are attached. Their function is to hold the small central roller 67 (Fig. 4), which they carry, in frictional engagement with the strip of paper that passes over the rollers 66 directly beneath, to prevent the paper from slipping. Also the free ends 75 of each of these rods is attached to flat metal rods 76, so as to release the roller 67 and stop the flow of paper. Thereby slack of paper beyond these feed rollers may catch up, as on disengagement of this roller 67 the pull on the paper ceases, and minute adjustment of the paper made. At the lower ends, the flat metal rods 76 (Fig. 3) have a notched recess 76a which can be latched to frame 64 and rollers 67 held disengaged from rollers 66 and no paper will be pulled from rolls 60, 61, 62 and 63, when press is in motion. In Fig. 28, the pawl 94 can be held disengaged from ratchet 92 by tightening wing nut 94a which will cause rollers 88 and 87 to remain motionless while press is in motion. These features are to permit the paper to remain stationary while the press is in motion in order to get the type and ink discs properly covered with ink before the press starts to feed paper through the press. This feature also applies to carbon paper rolls 228 (Fig. 24).

60 The paper strips then pass over rollers 66a down vertically and are kept taut sufficiently by compensator or tension bars 77 of U-shape. This bar 77 rests on the paper strip, there being one such bar for each separate strip. The paper strips then travel upwardly and over spaced rollers 78 at the head of the machine, thence back under the machine, and under rollers 79, then up over another roller 80. Thence the paper strips pass in spaced relation over the type and under the impression plate 23 that is disposed directly above the type for printing whatever is desired on the paper. Thence the strips of paper travel over a roller 82 adjacent the impression plate 23, upward and over other rollers 84 on the upper framework 64 of the machine.

70 Thence the paper travels toward the head end of the machine and other roller 85, and thence downward and under spaced knurled rollers 86,

The rollers are knurled to prevent smearing of the ink on the paper. Thence all of the sheets pass in overlying position over pull rollers 87 and under cooperating top rollers 88. Both of the rollers 87 and 88 are driven rollers so as to feed evenly.

A brake 130, consisting of members 295 and 295a (see Figs. 50 and 51) on end of shaft 93 (Fig. 28), has for its purpose to bring rollers 87 and 88 to a stop when pawl 94 turns said rollers to their completed revolutions.

As shown in Figs. 40 and 27, the strips of paper, one over the other, then pass under a clamp 90, which has spaced feet 91, adjustably mounted in slot 90a of the clamp, to engage the paper and hold it stationary for a moment while it is being cut by the automatically and mechanically driven shearing knife 89. Knife 89 cuts the paper into predetermined uniform size sheets. The feeding rollers 87 and 88 both come to a complete stop momentarily while the shearing knife 89 is in operation. Also the paper is not moving while the printing operation is being performed.

For example, for every sixteenth of an inch in circumference of the top and bottom feed rollers 88 and 87 heretofore described, there is a tooth on the ratchet-wheel 92. Ratchet-wheel 92 is mounted at the front of the machine on the same shaft 93 with the bottom feed roller 87. The feed rollers 87 and 88 are six inches in circumference. Thus there are ninety-six teeth in the ratchet wheel 92. For every tooth in the ratchet-wheel 92 the pawl 94 passes over on its counter-clockwise movement, $\frac{1}{16}$ of an inch of paper will be fed by rollers 88 and 87 when pawl 94 engages ratchet wheel 92 on its return clockwise movement.

A spring-actuated pawl 94 engages the ratchet-wheel 92 (Figs. 30 and 28). This pawl 94 is mounted on a bar 95 that extends to a hub 96, which is loosely mounted on the same shaft with the sprocket wheel 91. This loose hub 96 carries a sprocket wheel 97, over which extends a sprocket chain 98. The chain extends downwardly and has its forward end attached to an adjustable member 100 (Fig. 11) carried by a frame 101 which is mounted on a transverse shaft 50 on the lower portion of the machine (Fig. 8). This frame 101 has a scale 101a graduated in 16ths of an inch on the upper surface as shown in Fig. 11. Therefore in order to sever the paper, the adjustable member 100 is moved on scale 101a to correspond to the length of the sheet that it is desired to be severed by knife 89 shown in Fig. 39. In order to move the adjustable member 100, it is mounted on stub shaft 100e, which is held stationary at the desired site by the nut 100b, the nut 100c on the threaded shaft 101c which passes through the stub shaft 100e, is loosened and the shaft 101c is turned. Thereby the adjustable member 100 is moved to the desired setting on the scale 101a. The adjustment member 100 has an arm or crank-like member 100d, as shown in Figs. 11 and 12, which is attached to the end of the sprocket chain 98, as shown in Figs. 1, 2 and 30, which has been previously described.

Bar 101 is mounted on a transverse shaft 50 on the lower portion of the machine (Fig. 8). This same shaft 50 operates the ink plates 15 and 32 and the pull rollers 88 and 87. Every time the main shaft 9 turns over once the transverse shaft turns over twice. Consequently every time the main shaft turns over once it causes the printing mechanism to print twice, as the two point cam

10, carried by the main shaft 9 operates the type beds 13 to raise and lower them.

The other end of the sprocket chain 98 is attached to a roller 103 (Fig. 1) near the bottom of the machine, which roller is loosely mounted, and is on a stub shaft 104 to which a helical spring 105 is attached. The purpose of the spring is to cause the roller to reverse rotation after it has been rotated one way by the pull on the sprocket chain caused by the other end 98 of the sprocket chain being attached to the revolving or crank-like adjustment member 100d.

The two short top feed rollers 88 which press down on the bottom feed roller 87 are held in frictional engagement with the paper passing between said rollers. The top roller 88 is pressed by heavy springs 106 (Fig. 27) secured to arms 107 which carry the shaft 108 on which these rollers are mounted. Arms 107 are swingably mounted to another transverse shaft 109. As shown in Figs. 27 and 28, the springs 106 are connected to a screw 110 which has a nut 111 by which the tension of the springs 106 may be increased or decreased.

Referring to Figs. 27, 28, 29 and 31, there is a perforating wheel 81 which perforates the paper longitudinally. This wheel (or wheels) is mounted on an adjustable arm 81a which is attached to a collar and arm member 81b, and is, in turn, mounted on a shaft 81c. Shaft 81c has a down-turned arm 81d, as shown in Fig. 29. At the end of this arm 81d is an attached spring 81e. Spring 81e in turn is attached to the end of a threaded bolt 81f which is supported by an eye bolt 81g. The function of the arm 81d, spring 81e and bolt 81f, is to maintain the proper tension of the perforating wheel (wheels) 81 against the paper and the roller 87, as shown in Figs. 27 and 28.

After the paper is severed into strips of the desired length by the shearing knife it drops onto an endless belt 112 as shown in Fig. 34, which delivers the strips or sheets to a tray 113 at the front end of the machine. This endless belt 112 is mounted on rollers 112a. The roller 112a (Fig. 33) at one end carries a bevel gear 114 meshing with a bevel gear 115 on a vertical shaft 116. Shaft 116 carries a bevel gear 116a. Gear 116a in turn meshes with a bevel gear 117, on lower divided shafts 118 and 118a which extend horizontally of the machine. Shaft 118a has a bevel gear 119, meshing with a bevel gear 120 on the transverse shaft 50. Shaft 50 also drives the revolving adjustment bar 101. This device is attached to the sprocket chain 98 that runs over sprocket wheel 97. Wheel 97 has the arm and pawl that actuates the ratchet wheel 92 to move the feed rollers 88 and 87 that feed the paper to the shearing knife 89.

Also the machine has a counting mechanism which includes a large ratchet wheel 123, as shown in Figs. 33 and 36, which has 100 teeth, and with which an actuating pawl 124 is operatively engageable. Pawl 122 merely functions to prevent a reverse movement of ratchet 123 when the lug 123b is in contact with the four lugs 123a on ratchet 123. The ratchet wheel 123 is actuated by a bar 127. It is capable of adjustment by reason of a slot 128 in bar 127, and a bolt 129 engageable in slot 128. Bar 127 (Fig. 36) at its inner end carries a roller 131 which successively engages opposite rollers 132. Rollers 132 are mounted on a block 133 that is solidly mounted on the main shaft 9. Each revolution of the main shaft 9 causes the large ratchet wheel 123 to

move twice, or, in other words, each time the machine prints.

Ratchet wheel 123 has four lugs 123a. As ratchet wheel 123 turns one of the lugs 123a hits another lug 123b mounted on a stationary bracket 123c, as shown in Fig. 33. Lug 123b is hinged on bolt 123d which has an arm 123e through which passes the shaft 123f, having at its extreme end a fork 123h as shown in Fig. 38. Shaft 123f is moved by the arm 123e, forcing the fork against the flange of one of the gears 123g, thereby engaging the teeth of gears 123g mounted on divided shafts 118 and 118a, and at the end of member 118 there is a bevel gear 117 on the end nearest the head of the machine. Shaft 118a is constantly in motion. Bevel gear 117 engages bevel gear 118a mounted on the lower end of shaft 116, which has another bevel gear 115 on its upper end, which meshes with bevel gear 114, thereby turning the shaft on which rollers 112a are mounted, which rollers carry belt 112, and discharge paper into tray 113 in groups of 25's, 50's or 100's according to the number of lugs attached to ratchet wheel 123. If four lugs are used the sheets of paper are deposited in tray 113 in groups of 25, or if two lugs are used, paper will be deposited in groups of 50, or if one lug, in a group of 100.

Referring to Fig. 42, at the head end of the machine is a transverse shaft 134, which is operated by a hand wheel 135. Shaft 134 is threaded at its outer portion 136 and actuates a nut 137, to which bars extending up and down are pivotally connected at 138, forming a toggle lever 139. The upper end of the toggle lever 139 is connected to spaced cylinders 140 positioned on opposite sides of a belt 141. The lower end of the lower toggle lever member 142 is connected to similar spaced cylinders 143. These cylinders are positioned on opposite sides of belt 141. The belt 141 runs over the lower tapered pulley 145 near the bottom of the machine. This tapered pulley 145 is mounted on a shaft 146 which carries a bevel gear 147. Gear 147 meshes with another bevel gear 148 on the end of a shaft 149 extending longitudinally of the machine. As shown on Fig. 1, at its other end, the shaft 149 carries a gear 150 meshing with a gear 151 on another longitudinal shaft 152 which is driven from the main shaft 9 by sprocket wheels 153 and a chain 154.

As shown on Fig. 42, the upper tapered pulley 155 over which the belt 141 travels is mounted on a shaft 157 that extends transversely of the head of the machine. Shaft 157 carries a gear 158 which meshes with a loose gear 159 shown on Fig. 3, and which, in turn, meshes with a gear 160 on the lower elevated feed roller 66. The other rollers are in turn operatively connected with this lower feed roller 66 by a series of gears 162. There is a gear 163 on the rear end of the shafts 164 of each of these feed rollers 66, intermediate gears 162 connecting the gears 163 of one roller with the gears 163 of the roller immediately above.

Referring to Figs. 47 and 48, I have a perforating device 167 consisting of a perforating wheel 168 for perforating the strip of paper longitudinally. There may be one or several of these perforating wheels 168, each mounted on arms 169 which are mounted on collars 171, which are laterally adjustable on a transverse rod 170. Between collar 171 and collar 171a is mounted a spring 172. Spring 172 tends to hold the perforating wheel or disk 168 in operative engage-

ment with the paper to be perforated. To remove the perforating wheel 168 from contact with the paper, collar 171 is loosened and the wheel moved back from contact with the paper.

As shown in Figs. 47 and 48, in order to move the perforating wheel 168 horizontally the small set screw 171b, which holds the long collar 171c stationary on the shaft 170, is loosened. Thereby the whole perforating mechanism is aided to move horizontally on the shaft 170. This avoids the necessity of loosening the other collars 171 and 171a mounted on the long collar 171c, or the necessity of removing wheel 168 from a position of contact with the paper. The roller 84 has adjustment collars 84a which can be moved horizontally along the roller by loosening the small bolt 84b. These collars are adjusted to the edges of the paper which may vary in width. Therefore the necessity for these adjustable collars.

Roller 84, its supporting shaft 84c and the shaft 170, are mounted in a frame 167a, which is held in position on the frame 64 by the long hooked bolt 167g and the wing nut 167h. This frame 167a also is mounted on the shaft 167b and has at its opposite ends small toothed gears, 167c, which engage a small section of a gear track at 167d. Gear track 167d is mounted on the supporting framework 64 at either end of the frame 167a. This track is attached in stationary position to the supporting frame 64 by the set screw 167e.

In order to move the whole of the perforating mechanism 167, the wing nut 167h is loosened and the small knoblike wheel 167f, which is mounted at one end of the shaft 167b, is turned. Thereby the whole of the perforating mechanism 167 can be moved. This movement of the perforating mechanism 167 is only for minute adjustment in relation of the printed impression on the paper with the shearing knife.

Referring to Fig. 32, there is also another perforating disc 174, which is arranged to travel transversely of the machine and of the strips of paper. A perforating disc 174 is mounted on a carriage 175, which moves on a transverse rod 176, and has two upstanding guide posts 177, which slide on opposite sides of an upper transverse rod 178. A short transverse bar 179 is hingedly connected to carriage 175 to move it. Bar 179 is adjustably attached to an upstanding pivotally mounted bar 180, as shown in Fig. 39. Bar 180 passes between two fixed guide bars 181. Upstanding bar 180 has a bolt 182 which extends through a long slot 183 in a bar 184. The slot 183 in bar 184 (Fig. 39) enables the perforator 174 to remain motionless on either side of the paper while the paper is in motion. Bar 184 at its other end is connected with and actuated by the revolving cams 185, on the main shaft 9 of the machine at the head of the machine. This cam 185 has opposite cam projections 186. It functions to operate the shearing knife. It also functions to operate the paper clamp so that the clamp is applied a little ahead of the operation of the shearing knife 89.

The shearing knife 89 is linked at its end 187 by a bar 188 to a pivoted lever 189. Lever 189 carries a fixed roller 190, as shown in Fig. 41, that is actuated by the cam 185, and which causes the pivoted lever 189 to move upward, thereby causing the knife blade 89 to move downward, thus shearing the paper. The knife blade 89 is returned to its open position by a spring 193. At an intermediate point of shearing knife 89 is mounted a bar 191 which is attached to the

11

shearing knife 89 and constitutes a continuation of it.

To the rear end of extension bar 191 is attached a spring 192, as shown on Fig. 39, which functions to prevent vibration of the shearing knife in operation. Other springs 193 tend to hold the pivoted bar 189 in position to cause its roller 190 to engage with the surface of the revolving cam 185.

Referring to Figs. 40 and 41, cam 185 above described also engages a roller 195 on a transverse bar 196. Bar 196 is pivotally mounted at 197, near the front of the machine. At its rear end it is attached to a spring 198, which, in turn, is attached to the bed of the machine and tends to hold bar 196 in a down position. A long link bar 199 attached to this end of the bar is adjustably attached to the L-shaped end 200 of a rod 201 which extends transversely of the machine. Rod 201 is connected to a pair of transverse clamping bars 90 which have feet 91 that engage the paper sheets to clamp them in a stationary position while being severed by the shearing knife 89.

Referring to Fig. 6, the ink conveyor rollers 33 are adjustable vertically, by means of screws 205, which engage the ends 206 of rods 34 on which the rollers are mounted. The ink fountains 39, shown on Figs. 7 and 9, have rollers 28 that are intermittently operated by pawl and ratchet wheel mechanism 210. The pawl 211 is mounted on an arm 212 which is connected by a link 213 to an arm 214 on shaft 215, which extends longitudinally of the machine. Shaft 215 is adjustably connected by another arm 216 with a link 217 which connects with the vertical pivoted telescopic shaft 218 (Fig. 6).

Telescopic hollow shaft 218, 218a, which is pivoted at 218b, near its lower end, is connected by a pivoted link 219 with a disc 220 on the shaft 152, that runs longitudinally of the machine and which drives the ink rollers 33 and 31. This shaft 152 is driven directly from the main shaft 9 by sprocket wheel 221 and sprocket wheel 153 and chain 154 mounted on the main shaft 9. The upper end of the telescopic hollow shaft 218, 218a, is connected to a carriage element 225. Member 225 moves transversely on round rods 223 that carry the ink roller frame mechanism 224, of which these carriage elements at each end are a part.

Referring to Figs. 1 and 49, on the vertical frame work at the head of the machine, but under the paper rolls 60, 61, 62, and 63, may be mounted a series of carbon paper rollers 225, 226, and 227, carrying carbon paper rolls 228, if it is desired to have carbon paper interspersed with regular paper. They are driven by pulleys 229.

Referring to Figs. 1, 2, 24 and 49, carbon paper 228 is pulled up on the rollers 230, then under a tension roller 231, then downward by a compensator or floating tension bar 232. This floating tension bar 232 can travel either up or down in slot 232a (Fig. 1) which compensates roller 230 which may feed carbon paper too fast or too slow. Carbon paper 228 travels thence upward to a guide roller 233 and thence over the roller 84 on the longitudinal perforating device 167 (Figs. 47 and 24) where it then reaches its intended position between the two printed sheets of paper. From there it travels over certain rollers 85, thence downward to small knurled rollers 86, then toward the upper and lower pull rollers 87 and 88 and under the transverse perforating device 174.

12

(Fig. 24), and from there towards the shearing knife 89 where the paper is severed and deposited on the belt 112, shown in Figs. 33 and 34, which deposits it in the tray 113.

Occasionally it may be desirable to print both sides of the strips of paper, in which case the paper is threaded through the machine as shown in Fig. 25. In this case only two of the large rolls of paper 62 and 63 are used. The paper being pulled over the two lower of the four rollers 66 and then over the small rollers 66a, and downward by the compensator or floating tension bar 71 (Figs. 24 and 25). Thence the paper travels upward over the rollers 78, then under the first of the four rollers 79, thence onward to the second roller 79, where the two sheets of paper are dispersed and follow different routes through the machine.

In Fig. 25, the upper strip of paper passes under the second roller 79 and upward and over the second roller 80, and thence under the impression plate 23. It then passes upward and over the second roller 82. Then it travels back toward the head of the machine and over the first roller 82. Thence it travels down again and under the first impression plate 23, then it moves upward to the roller 84 where it meets the carbon strip that has been pulled from the carbon roll 228 up over the roller 230, mounted on a shaft which is operated by the pulley 229. Then the carbon is pulled downward by the compensator of tension bar 232. Thence it travels upward and over the small roller 233. From there it travels to the roller 84 where it meets the aforementioned strip of paper and travels downward to the small knurled rollers 86. From there it travels between the two pull rollers 87 and 88 and under the perforating wheel 174 and toward the knife 89. The sheets are severed by knife 89 and deposited on the moving belt 112. From the moving belt they are deposited in the tray 113.

The lower sheet of paper, as shown in Fig. 25, travels from the second roller 79 over a route similar to that of the sheet of paper above described, except that no carbon comes in contact with this strip of paper, since only one carbon strip is necessary when only two sheets of paper are printed, either on one or both sides.

Referring to Fig. 49, a mechanism for pulling the carbon paper from the rollers 228 is shown. There are three of these mechanisms as shown on Fig. 1. In Fig. 49, a roller 230 is mounted on the framework 64 by the eye-bolts 235. At one end of the shaft 234 is mounted a pulley 229. As shown in Fig. 1 the first of these mechanisms is the one nearest the left end of the machine, which mounts only one pulley 229. The following two mechanisms have two pulleys 229 each. Each of the pulleys 229 on these three mechanisms is connected by a belt 236. The third mechanism is connected by a belt 237 which is in turn connected to a pulley 238 mounted on the bottom one of the four shafts 164, as shown in Fig. 3. The shaft 164 gets its source of momentum from the gear 158 mounted on the shaft 157.

Adjacent to the roller 230 (Fig. 49) is the small tension wheel 231 whose function is to hold the paper taut against the roller 230 while in motion. This tension roller is attached to a shaft 239 by a collar 240 and by the arms 241. The shaft 239 is mounted on the frame 64 by eye-bolts 242. At the opposite ends of this shaft are arms 243 and 243a. The arm 243a has at its outer end a spring 244 which is attached to the frame 64.

Should it become necessary to remove the

tension roller 231 from contact with the paper, the arm 243 is moved upward. Thereby roller 231 is moved away from the paper, and permits the carbon paper to be adjusted. The spring 244 acts to return the tension roller 231 back into contact with the paper.

In Fig. 44 is shown one of the rollers 78 (also shown in Fig. 2) which are supported on the heavy metal bar 245 by the eye-bolts 246. Also mounted on the roller 78 is an adjustable collar 247 whose function and operation are similar to that of the collars 84a and 84b referred to in the description of Fig. 47. Directly above roller 78 is a small tension roller wheel or roller 248 mounted on the arms 249. Arms 249 are an integral part of the collar 250. Collar 250 in turn is mounted on a shaft 251 supported by eye-bolts 252, attached to the heavy metal bar 245.

In Fig. 46, at the outer end of the shaft 251, or the end towards the front of the machine, is an arm 257, which is an integral part of the shaft 251. At the outer end of this arm, a bolt 254 and a wing-nut 255 are located. At the end of the bolt 254 is attached a spring 256 which in turn is connected to the heavy metal bar 245. The shaft 251 is bent at its outer end to form an arm 257 which is connected to an adjustable member 258, shown in Fig. 2, by means of the bolts 259. This adjustable member is connected to an adjustment rod 260 by means of a bolt and wing nut 261. In turn it is connected to another rod 262 that is attached to a small wheel 263. Wheel 263 is mounted on the shaft 146 near the base of the machine. This small wheel 263 acts as a cam. The rod 262 is attached just off center of the wheel 263. As the wheel revolves, it causes the arms 257 to move downward, raising the small tension wheel 248 from contact with the roller 78, when the paper is in motion. When paper is not in motion, roller 78 engages wheel 248 and pulls the slack out and holds the paper taut while the printed impression is made by bed plate 13 and impression plate 23 (see Fig. 24).

Referring further to Fig. 2, Fig. 42 and Fig. 44, at the head of the machine and mounted on the shaft 146 is a large pulley 264 which is linked to another pulley 265. The pulley 265 is mounted on the shaft of the bottom-most one of the four rollers 78. These pulleys are linked together by the belt 266. Also mounted on this lower roller 78 and the three upper rollers 78 are smaller pulleys 267, which are all linked together by belts 268.

Due to the fact that the shaft 146 is constantly in motion and by means of the connected pulleys and belts just described, the rollers 78 are kept in constant motion.

In Fig. 45 there are illustrated the rollers 79, 80 and 82. Rollers 79 and 80 are mounted on a stationary upright member 269. The roller 82 is mounted on an adjustable member 270, by means of a bolt 271, which passes through a slot 272 in both the members 269 and 270. The adjustable member 270 serves to allow the roller 82 to be raised or lowered for minute adjustment.

Extending outward from the member 269 is an arm 273 supporting a small rod 274. On rod 274 is mounted a collar 275 and an arm 276 to which is attached a spring 277. Spring 277 is in turn connected to a belt 278 which passes over the roller 80 and downward where it is attached to another collar 279. Collar 279 is mounted on a shaft 280 mounted on an arm 281 extending from the side of the member 269. Extending from the collar 279 is an arm 282 which has a slot 283, as

shown in Fig. 28, through which passes the rod 284.

Referring to Figs. 45 and 27, rod 284 is connected by a flat L-shaped arm or member 285. Arm 285 is connected to the type bed 13 by means of the nuts and bolts 286. The function of this arm 285 is that as the type bed 13 moves upward, the rod 284 is moved upward also, forcing the arm 282 upward and turning the collar 280 on the shaft 279. Thereby the belt 278 is moved downward. This action turns the roller 80, thereby moving the paper which passes between the belt 278 and the surface of the roller 80. The purpose of this operation is to pull the slack out and hold the paper taut while printed impression is made by type bed 13 and impression plate 23 (Fig. 24). This augments the same purpose as rollers 78 and wheels 248 in Figs. 2 and 44, all of which is to get a good register of the printed impression.

The spring 277 acts to pull the belt back to its normal position, as shown in Fig. 45. The mechanism just described is mounted on the supporting framework 64, as shown in Fig. 1.

Referring to Figs. 10, 13, 24 and 25, there is shown a means by which the large rolls of paper 60, 61, 62 and 63, are attached to the upper framework 64 of the machine. To accomplish this, there is a shaft or shafts 287 supported on the framework 64 by the U-shaped bolts 288. In order to mount the rolls of paper 60, 61, 62 and 63, one of these rolls being shown in Fig. 10, a flanged cuplike bearing 289 is forced on this composition roller 290 on which the paper 61 is wound. Then the collar 291 is moved against the face of the flange of the flanged cuplike bearing 289 and fastened in stationary relation to the shaft 287 by the small set screw 292. To adjust the paper horizontally on the shaft 287 the set screw 292 is loosened and the whole roll of paper moved for minute adjustment.

Referring to Figs. 50 and 51, a hub or brake drum 293 is mounted on shaft 93, on which is also mounted the large roller 81, shown in Fig. 28, and held stationary by the set screw 294. The brake itself consists of two circular halves 295 and 295a. The half 295 is held in position around the hub or drum 293 by means of a long arm 296 which extends downward and attaches to the annular end 297. The piece 297 is in turn attached to a supporting member 298, which is similar to that shown in Figs. 27, 28, and 29. Other parts are omitted for clarity. Attachment is by means of the bolt and nut 300. The half brake 295a is attached to the half brake 295 by the hinge 301, and by the bolt 302, which passes through the two projecting pieces 303, which are an integral part of the two brake halves 295 and 295a.

The bolt 302 has a spring 304 which maintains the tension of the brake halves 295 and 295a, and also of the brake lining 305 against the hub or drum 293. The tension of the brake drum is adjusted by loosening or tightening the nut 306. The two brake halves 295 and 295a with the brake lining 305 are held on the hub or drum 293 by the circular plate 307, which acts as a flange and is attached directly to the hub or drum 293 by the two screws 308.

The purpose of this brake mechanism is to stop rollers 88 and 87 shown in Figs. 27 and 28 from turning immediately when pawl 94 (Figs. 28 and 30) has reached the limit of its clockwise movement.

We claim:

In a printing machine, the combination of an inking mechanism having an inking plate on both

sides of and in close proximity to the type, the said two inking plates supplying the inking rollers with ink, thereby enabling the inking rollers to deposit an even coverage of ink on the type form, an ink fountain, an auxiliary inking roller to convey ink from the ink fountain to the inking plate nearest to the ink fountain, a breaker plate disposed between the ink fountain and the inking plate for more evenly distributing the ink to the inking rollers, and means for vertically adjusting the inking rollers.
